UNITED STATES PATENT OFFICE.

ALVIN E. RUDY, OF FORT HUNTER, PENNSYLVANIA.

SLATE OR TILE ROOF.

No. 866,225.

Specification of Letters Patent.

Patented Sept. 17, 1907.

Application filed January 2, 1907. Serial No. 350,545.

To all whom it may concern:

Be it known that I, ALVIN E. RUDY, a citizen of the United States, residing at Fort Hunter, in the county of Dauphin and State of Pennsylvania, have invented 5 a new and useful Improvement in Slate or Tile Roofs, of which the following is a specification.

My invention consists in the manner in which the slates or tiles are applied to the roof, comprising the device for fastening and firmly holding the slate or tiling 10 in place.

In the accompanying drawings: Figure 1 is a perspective view of a detached portion of a roof with my improved method of fastening tile thereon; Fig. 2 is a detailed view of the fastening device, and Fig. 3 is a 15 sectional view on the line 3—3, Fig. 1.

In the process of covering the roof with slate or tile, the first course of slate or tile is applied in the usual manner, by nailing them close to the upper edges, to the sheathing of the roof, as shown in Fig. 1. A chalk-line 20 is then snapped horizontally along the length of this first course of slate, immediately below the line of nailing, and the second course of slate or tile is then applied. This course and the subsequent courses of slate are preferably put on diagonally, although they may be 25 put on very nearly horizontally if desired. Two diagonally opposite corners of each slate or tile are placed on the guiding chalk-line and are spaced about one-half inch apart, so as to permit the clamping-hook (see Fig. 2) to be placed between the corners of the adjacent 30 slates. This second course of slate is nailed at the point O, Fig. 1, and also receives nails carrying clamping-hooks at the upper corner of each tile or slate, at point K, Fig. 1. A clamping-hook is also placed at the point X, Fig. 1. These hooks hold the lower corners 35 of the third course of slate or tile in place. The third course of slate or tile is placed in like manner on the roof. This course and each succeeding course of slate or tile having but one nail-hole punched through each slate near its upper corner, and the slates or tiles are fastened 40 by means of one nail each, and one hook, the hook clamping and holding the lower corner of the slate diag-

onally opposite the point of nailing. This lower corner projects over the nail and the shank of the hook, which secures the lower corners of the succeeding course of slate. This method of nailing is continued 45 with each succeeding course of slate or tile to the apex of the roof.—The nails of the preceding course of slate forming the guide for the proper placing of the slate or tile in their positions.

It will thus appear that in each course after the two 50 first laid, each tile is held by a single nail through it, near one corner and by a hook engaging it near the diagonally opposite corner, which hook is carried by the single nail securing a slate in an underlying course and the head of which nail and the shank of the hook carried thereby is in the plane of and between tiles of a course intermediate that secured by said nail and that held by the hook on said nail.

In order to remove a broken slate, the projecting lower corner of the slate covering the nailing of the 60 broken slate, is easily pushed upward, and the nail of the broken slate is withdrawn and a new slate substituted.

I claim:

1. A slate or tile roof comprising slates or tiles held by 65 a single nail through each slate or tile near one corner, and near the diagonally opposite corner by a hook, whose shank lies in the plane of, and between the tiles of an underlying course, and which engages over the lower edge of the slate or tile held thereby.

2. A slate or tile roof comprising slates or tiles held by a single nail through each slate or tile near one corner and by a hook carried by the single nail of a slate or tile of an underlying course.

3. A slate or tile roof comprising slates or tiles held by 75 a single nail through each slate or tile near one corner and by a hook carried by the single nail of a slate or tile of an underlying course, the shank of which hook and the head of its nail lying in the plane of and between tiles of a course intermediate the two above mentioned.

ALVIN E. RUDY.
